THOMAS C. MALEY, OF DAYTON, OHIO, ASSIGNOR TO OHMER FARE REGISTER COMPANY, OF DAYTON, OHIO, A CORPORATION OF NEW YORK.

BELL-RINGING MECHANISM.

Application filed June 28, 1926. Serial No. 119,064.

This invention relates to a bell ringing mechanism and in particular is adapted for use in a taximeter, in which the flag may be moved either forwardly or reversely.

5 It is well known that in a modern taximeter, the flag is in a vertical position to denote that the cab is vacant or for hire, it is in first tariff position when it has been rotated clockwise 90° from the vertical position, it is hired but is not registering when it has been rotated 180° clockwise, and is in second tariff position when it has been rotated 270° clockwise. In many cities, only 10 one tariff is employed and in such cities the taximeter is adjusted so that it will be in first tariff position or its only tariff position when the flag is in the 90° or 270° position. The flag is only placed in the 180° position when the taxicab, after being hired, is detained on account of a breakdown, puncture, or for other cause not attributable to the passenger and for which he should not be charged. Ordinarily the flag is rotated clockwise only, but it is not infrequent that it 15 is necessary to rotate the flag anticlockwise, and for that reason taximeters are so constructed that the flag may be rotated anticlockwise from the 270° position into the 180° position, or from the 180° position into the 90° position.

If the flag were rotated in one direction only, a jumping cam might be employed to actuate a lever to ring a bell to denote that the flag has been moved from the position 20 in which it was to another position, but obviously a jumping cam could not be employed if the flag is to be rotated either clockwise or anti-clockwise.

It is the object of this invention to provide 25 means whereby a bell would be rung each time the flag is moved from one of its four positions into another position, regardless of whether the flag is rotated clockwise or anti-clockwise.

40 While I have shown the invention in connection with a taximeter, I do not limit its use thereto, for obviously it could be used in any relation in which it would be desirable to ring a bell to denote that a shaft has been rotated a predetermined distance, such as 45 90°. In the drawings, in which like refer-

ence characters are used throughout to denote similar parts;

Figure 1 is an elevational view looking 55 toward the rear of the taximeter, the full lines indicating the position in which the parts would be when the flag is in vacant position and the dotted lines showing the position in which the parts would be immediately prior to the ringing of the bell. 60

Figure 2 is a fragmentary detailed view, showing the parts in the position in which they would be at the instant the lever starts its movement to ring the bell, and

Figure 3 is a detailed cross sectional view 65 on the line 3—3 of Figure 1, looking in the direction of the arrows.

Referring more particularly to the drawings, the flag 10 is mounted on a conventional flag shaft 11, on which is rigidly mounted a 70 cam 12. The cam 12 is normally rotated in the reverse direction from that shown by the arrow in Figure 2. The cam 12 is, roughly speaking, a square, with each of the angles thereof slightly less than a right angle. Each 75 of the sides of the cam is composed of three straight lines, a line *a* which would be perpendicular to a line drawn from its midpoint to the center of the shaft 11, and lines *b* and *c* connected to the line *a* and forming almost 80 a straight angle therewith, which lines *b* and *c* extend from the line *a* to adjacent corners of the cam 12. The shaft 11 is mounted on the back wall of the taximeter, not shown.

A cross bar 13 is secured to the side walls, 85 not shown, of the taximeter and is rigid therewith. A lever 14 is pivotally connected to the cross bar 13 by means of a stud pin 15. The shape of the lever 14 is clearly shown in 90 Figure 1. The lever is normally pulled upwardly toward the cam 12 by means of the spring 16, secured to the lever 14 and to the cross bar 13. A clapper 17 is carried at the outer end of the lever 14, which clapper carries a sliding pin 18 which extends through 95 a hole 19 in the lever 14. The pin 18 is provided at its outer end with an abutment 20 held in place by means of a pin 21. Between the abutment 20 and the lever 14 is interposed a helical spring 22.

100 The lever 14 has pivoted thereon an oscillating détent 24 mounted on the pin 23 carried by

the lever 14. The detent 24 is located beneath the cam 12 and its movement to either side is limited by means of the stop pins 25 and 26. It is, however, normally held against the stop pin 25 by means of a spring 27. The upper portion of the detent 24 is bifurcated and the bifurcated extremities thereof are joined by an arc of a circle which receives one of the points of the cam 12.

10 The lever 14 carries a stop pin 28 which engages the under side of the cross bar 13 as the lever 14 moves upwardly, so that the clapper 17 will move against the tension of the spring 22 so as to strike and ring the bell 29, the 15 spring 22 immediately moving the clapper away from the bell, so that it can resound.

Figure 1 shows the parts in the position in which they would be when the flag is in its vertical position denoting that the cab is for hire. As soon as the cab is employed, the driver moves the flag 10 in a clockwise direction as viewed in Figure 1. The lowermost vertex of the cam 12 slides on the arc of a circle forming the left-hand arm of the bifurcated detent 24 moving the same against the stop pin 25. As soon as the detent 24 reaches the stop pin 25, the right-hand extremity 30 being subsequently in engagement with the parts *a* and *c* of the cam 12 the detent is depressed thereby moving the lever 14 downwardly against the tension of the spring 16. This motion continues until the vertex 31 passes over the right-hand extremity 30 of the detent 24 as shown in Figure 2, at which time the spring 16 pulls the lever 14 rapidly upward, so that the clapper 17 rings the bell 29 and the detent 24 moves in a clockwise direction, so that the vertex 31 rests against approximately the mid-portion of the arc connecting the arms of the detent 24. The ringing of the bell takes place at approximately the moment when the flag 10 reaches its 90°, 180°, 270°, or vacant positions.

The flag cannot be rotated reversely from its vacant position to the 270° position, nor from its 90° position to its vacant position being held against such movement by any suitable mechanism not shown. It can, however, be rotated from the 270° position into the 180° or the 90° positions. If it is reversely rotated, it would move according to the arrow shown in Figure 1, and the operation would be precisely the reverse of that described above.

55 It has been found in practice that if the spring 27 be omitted the device will function as a general rule, but sometimes the detent falls back of one of the vertices of the cam 12, in which case the bell would not be rung. The 60 spring 27, therefore, has the important function of positioning the detent 24 so as to insure the ringing of the bell every time the flag 10 is moved for 90 degrees.

While I have shown my invention, by way 65 of illustration, as forming a part of a taxim-

eter, I do not desire to limit myself to such a construction but desire to claim my invention broadly in whatever form it may be embodied which may fall within the spirit of the following claims.

Having now described my invention, I claim:

1. In a bell ringing mechanism, a star cam, means whereby said cam is rotated in either direction, a lever, a pivoted detent carried by 75 said lever and co-acting with said cam, spring means normally urging said detent toward said cam, a bell and means carried by said lever to ring said bell when the cam is rotated in either direction for a predeter- 80 mined distance.

2. In a bell ringing mechanism, a cam rotatable either forward or backwards, a pivoted lever, an oscillatable detent carried by 85 said lever co-acting with said cam, a spring urging said detent toward said cam, a bell and means carried by said lever to ring said bell when said cam is rotating for a predeter- minded distance in either direction.

3. In a bell ringing mechanism, a rotatable 90 cam, a lever, an oscillatable detent pivoted to said lever, a clapper carried by said lever, stop pins carried by said lever to limit the movement of said detent, said detent being bifurcated forming two arms separated by 95 an arcuate cutaway portion adapted to receive said cam, a bell and spring means attached to said lever to pull the same toward said bell when said cam passes beyond either of said arms.

4. In a bell ringing mechanism, a star-shaped cam adapted to be rotated in either a clockwise or anticlockwise direction, a lever, a clapper carried by said lever, a detent provided with arms, the extremities of which are adapted to engage the sides of said cam, a pin carried by said lever on which said detent is pivotally mounted, stop pins carried by 105 said lever to limit the movement of said detent, said cam moving said detent against one of the stop pins and then depressing said detent and lever as it is rotated until one of the points of the cam passes over the extremity of one of the arms, and spring means to thereupon trip said detent and move said lever toward said cam, and a bell adapted to be rung by the movement of said lever as it moves toward said cam.

5. In a bell ringing mechanism, a star-shaped cam adapted to be rotated in either a clockwise or anticlockwise direction, a lever, a clapper carried by said lever, a detent provided with arms, the extremities of which are adapted to engage the sides of said cam, a pin carried by said lever on which said detent is pivotally mounted, stop pins carried by said lever to limit the movement of said detent, said cam moving said detent against one of the stop pins and then depressing said detent and lever as it is rotated until one of 120 125 130

the points of the cam passes over the extremity of one of the arms, and spring means to thereupon trip said detent and move said lever toward said cam, and a bell adapted to be rung by the movement of said lever as it moves toward said cam, and means whereby said detent is normally urged toward one of said stop pins.

6. In a bell ringing mechanism, a rotatable cam substantially square but having each of its four angles slightly less than 90° , a pivoted detent having arms adapted to straddle any one of the vertices of said cam and to engage adjacent sides thereof, a lever on which said detent is mounted, a clapper carried by said lever, a bell, and means whereby said bell is rung and said detent tripped so

as to permit said bell to be rung when said cam is rotated in either direction a predetermined distance.

7. In a bell ringing mechanism, a rotatable cam, a lever, a detent carried by said lever and serving as a tripping mechanism, a bell, a bell clapper carried by said lever, means whereby said detent is tripped and said lever urged rapidly toward said bell, means whereby the motion of said lever is arrested before the clapper reaches the bell, and spring means to permit said clapper to touch said bell and to cause said clapper to then be withdrawn from contact with said bell.

In testimony whereof I affix my signature.

THOMAS C. MALEY.
